US0D1009936S

(12) **United States Design Patent** (10) **Patent No.:** **US D1,009,936 S**
(45) **Date of Patent:** **** Jan. 2, 2024**

(54) **RAM-AIR INTAKE**

(71) Applicant: **Velossa Tech Engineering Inc.**, Davie, FL (US)

(72) Inventor: **Dan Joseph Becker**, Davie, FL (US)

(73) Assignee: **Velossa Tech Engineering Inc.**, Davie, FL (US)

(**) Term: **15 Years**

(21) Appl. No.: **29/703,228**

(22) Filed: **Aug. 26, 2019**

(51) LOC (14) Cl. **15-01**

(52) U.S. Cl.

USPC **D15/5**

(58) **Field of Classification Search**

USPC D15/1, 5; D23/384, 386, 387, 393, 394, D23/266, 263, 262, 260, 264

(57) **CLAIM**

The ornamental design for a ram-air intake, as shown and described.

DESCRIPTION

FIG. 1 is a front top perspective view of a ram-air intake showing my new design;

FIG. 2 is a front elevation view thereof;

FIG. 3 is a rear elevation view thereof;

FIG. 4 is a bottom view thereof;

FIG. 5 is a top view thereof;

FIG. 6 is a right-side elevation view thereof; and,

FIG. 7 is a left-side elevation view thereof.

The broken lines illustrate portions of the ram-air intake that do not form a part of the claimed design.

1 Claim, 7 Drawing Sheets
